UNITED STATES PATENT OFFICE.

EDWARD A. JUDD, OF NEW BRITAIN, CONNECTICUT, ASSIGNOR TO THE CORBIN CABINET LOCK COMPANY, OF SAME PLACE.

TRUNK-LOCK..

SPECIFICATION forming part of Letters Patent No. 521,471, dated June 19, 1894.

Application filed November 3, 1893. Serial No. 489,912. (No model.)

To all whom it may concern:

Be it known that I, EDWARD A. JUDD, a citizen of the United States, residing at New Britain, in the county of Hartford and State of Connecticut, have invented certain new and useful Improvements in Hasp Locks and Guards, of which the following is a specification.

My invention relates to improvements in hasp locks and guards, and the objects of my improvement are simplicity and economy in construction and particularly to produce the hasp plate and guard of sheet metal, whereby an efficient and neat appearing lock is produced at a small cost.

In the accompanying drawings: Figure 1 is a front elevation of my lock complete. Fig. 2 is a central vertical section of the same with the lower part of the hasp in elevation. Fig. 3 is a rear elevation of the hasp plate and hasp. Fig. 4 is a front elevation of the guard and keeper. Fig. 5 is a plan view of the blank from which said guard and keeper is struck up. Fig. 6 is a front view showing the result of the first operation upon the blank, Fig. 5. Fig. 7 is a plan view of the blank for the hasp plate. Fig. 8 is a front elevation of the result of the first operation upon said blank, and Fig. 9 is a like view showing the result of the second operation.

A designates the hasp having secured thereto, or built within it, a lock of any ordinary construction with the lock bolt 10 arranged to be extended outwardly from its lower end. 35 As is usual with this class of locks, the hasp is also provided with a spring 11, one end of which presses upon the cross bar 12 of the hasp plate B with a constant tendency to force the hasp outwardly when released. The hasp plate B is struck up from a sheet metal blank, Fig. 7, in suitable dies by one or more operations, resulting in the form shown in Fig. 9. The surplus metal is then removed from its edge. This hasp plate is formed 40 with a bead 16 which is substantially in the form of an inverted U in front elevation with the dowel pins 13 formed at the ends of said bead as best shown in Fig. 3. The space inclosed by this bead is to receive the upper end 45 of the hasp A. A portion of the hasp plate above the cross bar 12 is removed for conven-

ience in assembling the parts, and the inner wall of the bead by the sides of this opening is recessed to receive the pintle 14 of the hasp, as shown in Fig. 3. In order to prevent the hasp from becoming accidentally detached during transportation, the plate 15 is secured by means of a rivet upon the inside of the bead so as to cover the ends of the pintle 14 and hold it in place. While I prefer to make the dowel pins in one and the same piece with the hasp plate, it is evident that they may be separably formed and rigidly secured thereto if desired.

I form the guard and keeper from a plate 65 of sheet metal as shown in Fig. 5, the same being struck up to form the U shaped bead 17 with the space inclosed by said bead of a suitable form to receive and hold the lower end of the hasp as shown in Figs. 1 and 2, 70 the upper ends of the bead being widened to form inwardly projecting shoulders for being engaged by the widened lower end of the hasp A. It is best to strike this blank first into the form shown in Fig. 6 and then again strike 75 it to flatten the flange outside of said bead, after which its edges may be trimmed and the central part punched out, thereby changing the metal from the form shown in Fig. 6 to that shown in Fig. 4. In the inner wall at 80 the lower part of this bead 17, I form a slot or mortise 18^a as shown in Fig. 2 to receive the end of the lock bolt 10 and enable this part of the lock to serve as a keeper for said bolt. The upper ends of the bead 17 are left 85 open to form sockets 18 for the reception of the dowel pins 13. This guard or keeper protects the lower part of the hasp and its lock from injury by a continuous bead around it, preferably with a slight flange upon its outer 90 and inner edges. Locks of this general class having a combined guard and keeper with the lock attached to the hasp and also provided with a dowel system are old when the hasp plate and combined guard and keeper are 95 formed of cast metal, and I hereby disclaim the same.

By my improvements I form the hasp plate with its cross bar 12 in the same piece with the other parts and I am enabled to form the same cheaply by striking it up from sheet metal. I also form the guard and keeper by

striking it up from sheet metal, and by these improvements I economize in labor and necessarily modify the form and construction of the parts whereby I produce a neat and efficient lock of this class.

5 I claim as my invention—

1. The herein described hasp lock, consisting of the hasp plate B having a bead 16 struck up from sheet metal the combined lock and hasp pivoted within the space inclosed by said bead, and the combined guard and keeper with the continuous struck up bead 17 with its ends meeting the ends of the bead in said hasp plate, substantially as described and for 15 the purpose specified.

2. In a hasp lock, the hasp plate B having the bead 16 in the form of an inverted U and the integral dowel pins 13 projecting from the lower ends of said bead all struck up from a

single piece of sheet metal, substantially as 20 described and for the purpose specified.

3. In a hasp lock the hasp plate B having the bead 16 in the form of an inverted U, dowel pins projecting from the lower ends of 25 said bead, pintle recesses in the inner side walls of said bead and the cross bar 12 connecting the lower ends of said bead, the combined lock hasp pivoted within the space inclosed by said U shaped bead, its pintle resting in said side recesses of said bead and projecting into the hollow part thereof, and the securing plate 15 within said hollow bead, substantially as described and for the purpose specified.

EDWARD A. JUDD.
